US00D930661S

(12) **United States Design Patent** (10) Patent No.: **US D930,661 S**
(45) Date of Patent: **** Sep. 14, 2021**

(54) **ELECTRONIC DEVICE WITH GRAPHICAL
USER INTERFACE**

(71) Applicant: **Apple Inc.**, Cupertino, CA (US)

(72) Inventors: **Lee Broughton**, Santa Cruz, CA (US); **Alan C. Dye**, San Francisco, CA (US); **Jonathan P. Ive**, San Francisco, CA (US); **Behkish Johnnie Manzari**, San Francisco, CA (US); **Pani Page**, San Francisco, CA (US); **Grant R. Paul**, San Francisco, CA (US); **William A. Sorrentino, III**, San Francisco, CA (US); **Andre Souza Dos Santos**, Santa Clara, CA (US); **Christopher Wilson**, San Francisco, CA (US)

(73) Assignee: **Apple Inc.**, Cupertino, CA (US)

(**) Term: **15 Years**

(21) Appl. No.: **29/694,349**

(22) Filed: **Jun. 10, 2019**

Related U.S. Application Data

(63) Continuation of application No. 29/616,884, filed on Sep. 9, 2017, now Pat. No. Des. 851,111.

CLAIM

The ornamental design an electronic device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface showing the claimed design.

The broken lines in the FIGURE show an electronic device having a display screen, and form no part of the claimed design.

**1 Claim, 1 Drawing Sheet
(1 of 1 Drawing Sheet(s) Filed in Color)**
